APPARATUS FOR DISCHARGING LIQUEFIED
GASES FROM A VESSEL BELOW ATMOS-
PHERIC TEMPERATURE

William Lane De Baufre, Lincoln, Nebr.

Application August 12, 1935, Serial No. 35,825

18 Claims. (Cl. 62—1)

This invention relates to the art of automatically controlling the discharge of liquefied gases from a vessel below atmospheric temperature in order to maintain a nearly constant liquid level in 5 therein. It is particularly applicable to plants for rectifying atmospheric air into more or less pure oxygen and nitrogen. In the air separation plant described in U. S. Patent No. 1,951,185, issued March 13, 1934, for example, there are two 10 places where the liquid level should be maintained as nearly constant as possible by discharging liquefied gases therefrom. These places are the pot E at the lower end of preliminary tray section F and the pot at the lower end of ex- 15 changer K. Heretofore, the liquefied gases in these pots have been discharged through manually controlled valves 31 and 44 respectively. Automatic control of the discharge of these liquefied gases would eliminate the necessity of manual control and would also maintain conditions 20 of operation more nearly constant. As the effectiveness of rectification is increased by more nearly constant conditions of operation, such automatic means would be an improvement over manual control in increasing the purities of the products of rectification.

In applying such automatic means to the control of the discharge of liquefied gases considerably below room temperature, certain difficulties 30 are encountered which are not met with in plants operating at or above atmospheric temperature. These difficulties are mainly due to accumulation of small quantities of carbon dioxide and particularly of moisture which in freezing cement 35 parts of an apparatus together and render any mechanism inoperative.

One object of the present invention is to provide a mechanism for automatically discharging liquefied gases from a vessel below atmospheric temperature with minimum danger of becoming 40 inoperative by freezing of moisture upon it.

Another object of the invention is to provide a mechanism which can be easily freed from such frozen moisture.

Another object of the invention is to provide 45 means for freeing the mechanism, operated manually from outside the thick layer of insulating material which necessarily covers these low temperature vessels to reduce heat leak into them from the atmosphere.

Another object of the invention is to manually 50 control the discharge of liquefied gases whenever that may be desirable under abnormal operating conditions of plant or when the automatic control mechanism is inoperative for any reason.

Another object of the invention is to arrange for movement of the vessel from which liquefied gases are discharged, with contraction and expansion of the plant due to cooling and heating.

Another object of the invention is to facilitate 5 defrosting the mechanism for discharge of liquefied gases.

The foregoing, together with such other advantages as hereafter appear or are incident to the invention, are realized by the construction illustrated in preferred form in the drawing, wherein Fig. 1 shows a cross-sectional elevation of the complete apparatus and Fig. 2 shows a modification of one detail thereof.

Referring to Fig. 1, the vessel in which a nearly 15 constant liquid level is to be maintained by discharge of liquefied gases therefrom has a metal wall 1. Two flexible pipes 2 and 3, one above the liquid level 4 and the other below this level, connect vessel 1 to auxiliary vessel 5. The liquid 20 level within vessel 5 will be the same as in vessel 1 except for frictional resistance to flow of the liquid through pipe 3 and the presence of gas bubbles in either vessel.

The mechanism for controlling the discharge 25 of liquefied gases automatically and manually is attached to auxiliary vessel 5. The head 6 is bolted to flanges 7 of vessel 5. An inclined passage-way 8 extends through the partition in head 6 from the space within vessel 5 to the 30 space into which the liquefied gases are to be discharged.

At the lower and inner end of passage-way 8 is a flat narrow circular seat on which valve disk 9 rests when float 10 is not buoyed up by liquefied 35 gases within vessel 5. When the liquid level of the liquefied gases rises within vessel 5, float 10 also rises and lifts valve 9 from its seat, being attached thereto by the bent lever 11 pivoted at 40 12.

The upper and outer end of passage-way 8 has a conical seat for valve 13. A pin 14 projects from valve 13 part way through passage-way 8. When valve 13 approaches its seat at the outer end of passageway 8, pin 14 enters the depression 45 shown, in valve disk 9 and forces this valve disk away from its seat the inner end of passage-way 8. Thus, valve 13 must be wide open for valve 9 to be nearly closed and automatically control the discharge of liquefied gases from vessel 5 in order to 50 maintain a nearly constant liquid level therein. When valve 13 is nearly closed to manually control the discharge of liquefied gases, valve 9 is forced open so wide as to have little effect upon the rate of discharge. The liquefied gases dis- 55

charged from vessel 5 leave the apparatus through pipe 15.

The stem 16 of valve 13 extends upwards through inclined sleeve 17. This sleeve is held rigidly in place on head 6 by nut 18. At the outer end of sleeve 17 is a packing box with gland and nut for holding packing material 19 between sleeve 17 and stem 16 to prevent leakage of liquefied gases along the annular space between sleeve 10 and stem.

Beyond the packing nut on the outer end of sleeve 17, stem 16 of valve 13 is enlarged at 20 and threaded to engage nut 21 which is held in place by yoke 22 attached to sleeve 17. Handwheel 23 is mounted on the end of stem 16.

Casing 24 holds heat insulating material 25 around vessels 1 and 5 and other parts of the apparatus shown. Sleeve 17 extends through insulating material 25 from head 6 at very low temperature to packing material 19 and yoke 22 at about atmospheric temperature.

In order to reduce heat leak from the atmosphere through stem 16 and sleeve 17 to the liquefied gases discharged from vessel 5, both stem and sleeve are made of a solid solution of copper and nickel which has considerably less heat conductivity than either metal in its pure state. This is in general true for all solid solutions. This particular solid solution has the further advantage that it does not rust or corrode in moist air. Stem 16 is made hollow as shown to further reduce conduction of heat along the stem.

Pipe 26 extending through insulating material 25 from head 6 to valve 27 outside of casing 24, 35 is a drain pipe for the space into which the liquefied gases are discharged through passage-way 8.

In Fig. 2, the corresponding parts have the same numbers as in Fig. 1. The passage-way 8, however, extends horizontally through the partition in head 6. Valve stem 16 and sleeve 17 are also in horizontal positions. Valve 13 is arranged not only to seat upon the outer end of passage-way 8 when moved to the left, but also to seat upon the inner end of sleeve 17 when moved to the right into the position shown. In the position shown, leakage of liquefied gases is prevented between stem and sleeve irrespective of the tightness of any packing material at the outer end of sleeve 17. In case such a back seating valve is employed for manual control of discharge of liquefied gases, there will be no advantage in enlarging the stem at the outer end as shown at 20 in Fig. 1.

During normal operation of a plant for rectifying atmospheric air and equipped with automatic and manual controls for discharge of the liquefied gases as shown in Fig. 1 or Fig. 2, the manually operated valve would be withdrawn from the outer end of the passage-way 8 for discharge of liquefied gases as shown in these two figures. The discharge of liquefied gases would then be automatically controlled by the valve and float-lever mechanism shown, so as to maintain a nearly constant liquid level of the liquefied gases within vessels 1 and 5. Should the rate of accumulation of liquefied gases increase or decrease, the liquid level would slightly rise or fall until the opening between valve 9 and the seat at the inner end of passage-way 8 would be just sufficient to discharge the liquefied gases at the same rates as they accumulate.

During normal operation of the plant, there is little danger of the automatic control mechanism sticking in any one position. But should this occur, handwheel 23 can be rotated to move valve

13 towards its seat at the outer end of passage-way 8 until pin 14 engages the depression in valve disk 9 and forces the disk to move away from its seat at the inner end of passage-way 8. As soon as the mechanism is thereby freed of its sticking, 5 manually controlled valve 13 may be withdrawn.

When the plant is shut down for defrosting, accumulated liquids may be withdrawn through the various drain pipes and valves provided for the purpose. Liquid in tube 15 and the space 10 surrounding valve 13 may be withdrawn through drain pipe 26 and valve 27.

While moisture is being removed by blowing warm air through the plant, drain valve 27 may remain open until the air blowing out of it feels 15 warm, thus indicating all moisture to be removed from pipe 15 and the space surrounding valve 13. If the space within vessel 1 is under pressure, valve 9 will be forced against its seat. By manual operation of valve 13, valve 9 can be forced from 20 its seat by pin 14, thereby permitting warm air in vessel 1 to blow through vessel 5 and dry the float-lever mechanism therein.

With the construction shown in Fig. 1, valve 13 and stem 16 can be completely withdrawn through sleeve 17 and nut 21. Warm air from pipe 15 will then blow through sleeve 17 and dry it. By inserting a small diameter rod through nut 21 and sleeve 17, valve 9 may be pushed away from its seat to permit warm air within vessel 1 to blow 30 through sleeve 17. Valve 13 and stem 16 can then be replaced and repacked if necessary, ready for starting the plant when satisfactorily defrosted. All this can be done without disturbing insulating material 25.

Should the drying not be thoroughly done, but some moisture remain between valve 9 and its seat or even in the bearings at 12, this moisture will freeze upon recooling the plant to operating temperatures. The float-lever mechanism 11 40 would then be held rigid by ice in the bearings at 12 and between valve 9 and its seat, thus rendering valve 9 inoperative. By manually operating valve 13, pin 14 can be pushed against valve disk 9, thereby forcing this valve from its seat 45 and breaking the bond of ice between valve 9 and its seat and also breaking any ice bond in the bearings at 12. The bearings at 12 should be made a loose fit to enable the latter to be easily 50 done. The seat of valve 9 is made flat and narrow to provide little surface for holding moisture. Valve disk 9 has a depression facing passage-way 8 for pin 14 to engage in forcing valve 9 from its seat.

During normal operation, there is a tendency 55 for liquefied gases surrounding valve 13 to flow along the annular space between stem 16 and sleeve 17. The outer ends of stem 16 and sleeve 17 are nearly at atmospheric temperature and there exists a temperature gradient along stem 60 16 and sleeve 17 from nearly atmospheric temperature at the outer end to the low temperature of the liquefied gases at the inner end. Any liquefied gases flowing along stem 16 and sleeve 17 to a region of higher temperature will absorb 65 heat therefrom, vaporize and return to valve 13. This circulation would materially increase heat leak into the plant with corresponding loss of efficiency. Two different methods of avoiding such loss are shown in Fig. 1 and Fig. 2.

In Fig. 1, sleeve 17 is inclined in extending through insulating material 25 and stem 16 passes upwards from valve 13 through sleeve 17. With packing material 19 making a gas tight joint between sleeve 17 and stem 16, there is no flow 75

of gas longitudinally. The gases in the annular space between sleeve 17 and stem 16 remain stagnant. Conduction of heat along sleeve and stem vaporizes a small amount of liquefied gases at

5 valve 13, and this vapor must escape through pipe 15. The liquid level of the liquefied gases therefore remains at the level of the outlet to pipe 15. The inclined position of sleeve 17 and stem 16 prevents liquefied gases entering the 10 annular space between them. This construction therefore eliminates abnormal heat leak due to vaporization of liquefied gases flowing longitudinally between sleeve and stem. The inclined position of sleeve 17 and stem 16 necessitates an 15 equal inclination of passage-way 8 for pin 14 to project therethrough.

In Fig. 2 flow of liquefied gases into the annular space between sleeve 17 and stem 16 is prevented by valve 13 back seating upon the end 20 of sleeve 17 when it is moved as far as possible to the right to the position shown. Sleeve 17 and stem 16 may then be in a horizontal position with a simpler construction of head 6.

In any case, head 6 could be directly attached 25 to vessel 1 instead of to auxiliary vessel 5. The latter arrangement, however, enables the manual control handle 23 to be more conveniently located. Thus, auxiliary vessel 5 may be placed for the most convenient location of handle 23 30 and pipes 2 and 3 run to vessel 1, the restrictions being that auxiliary vessel 5 must be at the proper level and pipes 2 and 3 must extend above and below the desired liquid level respectively, preferably without liquid or vapor traps. Then, 35 as vessel 1 moves up and down by reason of expansion and contraction due to temperature changes in the plant, this movement may be taken care of by making pipes 2 and 3 sufficiently long and flexible, auxiliary vessel 5 being supported in a position substantially fixed relative to casing 24 through which sleeve 17 projects.

Passage-way 8 may be formed of a removable bushing to facilitate repairs.

I claim:

45 1. Apparatus for discharging liquefied gases from a vessel below atmospheric temperature and covered with insulating material, including a partition between the space within said vessel and the space into which said liquefied gases are discharged, a passage-way through said partition, a valve and seat at the inner end of said passage-way, means for opening and closing said valve with rise and fall in the level of said liquefied gases, a second valve and seat at the outer 50 end of said passage-way, a sleeve through said insulating material and a stem from said second valve extending through said sleeve for manually operating said second valve outside said insulating material.

60 2. Apparatus for discharging liquefied gases from a vessel below atmospheric temperature and covered with insulating material as in claim 1, including means for holding the first valve off its seat when said second valve is nearly closed.

65 3. Apparatus for discharging liquefied gases from a vessel below atmospheric temperature and covered with insulating material as in claim 1, including a pin projecting from the manually operated valve through said passage-way whereby the valve at the inner end of said passage-way is held off its seat when the manually operated valve is nearly closed.

4. Apparatus for discharging liquefied gases from a vessel below atmospheric temperature and covered with insulating material as in claim

1, including packing material between said sleeve and said stem to prevent leakage of said liquefied gases.

5 5. Apparatus for discharging liquefied gases from a vessel below atmospheric temperature and covered with insulating material as in claim 1, including a seat on the inner end of said sleeve for said second valve whereby leakage of said liquefied gases between said sleeve and said stem may be prevented by closing said second valve on 10 said seat.

15 6. Apparatus for discharging liquefied gases from a vessel below atmospheric temperature and covered with insulating material as in claim 1, wherein said sleeve and said stem are made of a solid solution of metals having lower heat conductivity than pure metals.

20 7. Apparatus for discharging liquefied gases from a vessel below atmospheric temperature and covered with insulating material as in claim 1, wherein said stem is made hollow to reduce 25 conduction of heat along said stem.

25 8. Apparatus for discharging liquefied gases from a vessel below atmospheric temperature and covered with insulating material as in claim 1, including an enlarged part of said stem with threads thereon beyond said sleeve, and a nut engaging said threads and held by a yoke to said sleeve whereby said valve is opened and closed 30 by rotating said stem and said stem can be removed through said nut.

35 9. Apparatus for discharging liquefied gases from a vessel below atmospheric temperature, and covered with insulating material, including a partition between the space within said vessel and the space into which said liquefied gases are discharged, a passage-way through said partition, a valve and seat at the inner end of said passage-way, means for opening and closing said valve with rise and fall in the level of said liquefied gases, and means extending through said insulating material for manually raising said valve from said seat comprising a sleeve through said insulating material and a stem extending through said sleeve whereby heat leak is reduced 40 through said means for raising said valve from said seat.

45 10. Apparatus for discharging liquefied gases from a vessel below atmospheric temperature, including a partition between the space within said vessel and the space into which said liquefied gases are discharged, a passage-way through said partition, a disk valve seating on a narrow flat seat at the inner end of said passage-way, means for operating said valve by variations in the liquid level of said liquefied gases within said vessel, and a manually operated valve seating at the outer end of said passage-way, wherein said disk valve has a depression therein and a pin projects from the manually operated valve into 50 said depression to hold the disk valve open when the manually operated valve is nearly closed.

55 11. Apparatus for discharging liquefied gases from a vessel below atmospheric temperature and covered with insulating material, including a partition between the space within said vessel and the space into which said liquefied gases are discharged, an inclined passage-way extending upwards through said partition, a valve and seat at the lower end of said passage-way, means for 60 opening and closing said valve with rise and fall in level of said liquefied gases, a second valve and seat at the upper end of said passage-way, an inclined sleeve through said insulating material, a stem from said second valve extending upwards 65

- through said sleeve for manually operating said second valve, and packing material between said sleeve and said stem to prevent leakage of said liquefied gases.
5. 12. Apparatus for discharging liquefied gases from a vessel below atmospheric temperature and covered with insulating material as in claim 11, including means for holding the first valve off its seat when said second valve is nearly 10 closed.
13. Apparatus for discharging liquefied gases from a vessel below atmospheric temperature and covered with insulating material, including a partition between the space within said vessel 15 and the space into which said liquefied gases are discharged, an inclined passage-way extending upwards through said partition, a valve and seat at the lower end of said passage-way, means for opening and closing said valve with rise and fall 20 in level of said liquefied gases, a second valve and seat at the upper end of said passage-way, an inclined sleeve through said insulating material, a stem from said second valve extending upwards through said sleeve for manually operating said second valve, packing material between said sleeve and said stem to prevent leakage of said liquefied gases, and a pin projecting from said second valve through said passage-way whereby the first valve is held off its seat when 25 said second valve is nearly closed.
30. 14. Apparatus for discharging liquefied gases from a vessel below atmospheric temperature and covered with insulating material, including a partition between the space within said vessel and the space into which said liquefied gases are discharged, an inclined passage-way extending upwards through said partition, a valve and seat at the lower end of said passage-way, a float partly immersed in said liquefied gases, a lever 35 connecting said valve and said float whereby a rise or fall of said float with the level of said liquefied gases opens or closes said valve, a second valve and seat at the upper end of said passage-way, an inclined sleeve through said insulating material, a stem from said second valve extending 40 upwards through said sleeve for manually operating said second valve, packing material between said sleeve and said stem to prevent leakage of said liquefied gases, and a pin projecting from said second valve through said passage-way whereby the first valve is held off its seat when 45 said second valve is nearly closed.
50. 15. Apparatus for discharging liquefied gases from a vessel below atmospheric temperature and covered with insulating material, including a partition between the space within said vessel and the space into which said liquefied gases are discharged, an inclined passage-way extending upwards through said partition, a valve and seat at the lower end of said passage-way, a float partly immersed in said liquefied gases, a lever connecting 55 said valve and said float whereby a rise or fall of said float with the level of said liquefied gases opens or closes said valve, a second valve and seat at the upper end of said passage-way, an inclined sleeve through said insulating material, a stem from said second valve extending upwards through said sleeve for manually operating said second valve outside said insulating material, an enlarged part of said stem with threads thereon beyond said sleeve and a nut engaging said threads and held by a yoke to said sleeve whereby said valve is opened and closed by 60 rotating said stem and said stem can be removed through said nut.

gases opens or closes said valve, a second valve and seat at the upper end of said passage-way, an inclined sleeve through said insulating material, a stem from said second valve extending upwards through said sleeve for manually operating said second valve, packing material between said sleeve and said stem to prevent leakage of said liquefied gases, an enlarged part of said stem with threads thereon beyond said sleeve, a nut engaging said threads and held by a yoke to said sleeve whereby 10 said second valve is moved longitudinally by rotating said stem and said stem may be removed through said nut, and a pin projecting from said second valve through said passage-way whereby the first valve is held off its seat when said second 15 valve is nearly closed.

16. Apparatus for discharging liquefied gases from a vessel below atmospheric temperature, including a partition between the space within said vessel and the space into which said liquefied 20 gases are discharged, a passage-way through said partition, a valve seating at the inner end of said passage-way, means for operating said valve by variations in liquid level of said liquefied gases within said vessel, a manually operated valve seating at the outer end of said passage-way and including means for holding the first mentioned valve off its seat when the manually operated valve is nearly closed whereby variations in liquid 25 level of said liquefied gases within said vessel are 30 controlled by said manually operated valve.

17. Apparatus for discharging liquefied gases from a vessel below atmospheric temperature and covered with insulating material, including a casing surrounding said insulating material, an auxiliary vessel fixed relative to said casing, means for varying the rate of discharge of said liquefied gases from said auxiliary vessel, means for operating the same from without said insulating material, and flexible connections between the first 40 mentioned vessel and said auxiliary vessel for flow of liquid and vapor to said auxiliary vessel whereby the first mentioned vessel may move up and down relative to said casing by reason of expansion and contraction due to temperature 45 changes.

18. Apparatus for discharging liquefied gases from a vessel below atmospheric temperature and covered with insulating material, including a partition between the space within said vessel and the space into which said liquefied gases are discharged, a passage-way through said partition, a valve for closing said passage-way, a sleeve through said insulating material, a stem from said valve extending through said sleeve for manually operating said valve outside said insulating material, an enlarged part of said stem with threads thereon beyond said sleeve and a nut engaging said threads and held by a yoke to said sleeve whereby said valve is opened and closed by 60 rotating said stem and said stem can be removed through said nut.

WILLIAM LANE DE BAUFRE.
